DESIGN FOR A KITCHEN UTENSIL HANDLE

Frederick K. Storm, Los Angeles, Calif., assignor
to Adel Precision Products Corp., a corporation
of California

Application April 9, 1945, Serial No. 118,904

Term of patent 14 years

(Cl. D44—29)

To all whom it may concern:

Be it known that I, Frederick K. Storm, a citizen of the United States and residing at Los Angeles, in the county of Los Angeles and State of California, have invented a new, original, and ornamental Design for Kitchen Utensil Handle, of which the following is a specification, reference being had to the accompanying drawing forming part thereof, in which:

Fig. 1 is a top plan view of a kitchen utensil handle showing my new design;

Fig. 2 is an elevational view of one side of said handle;

Fig. 3 is a bottom plan view of said handle;
Fig. 4 is an elevational view of the other side of said handle;

Fig. 5 is a front end elevation of said handle;
and

Fig. 6 is a rear end elevation of said handle.

I claim:

The ornamental design for a kitchen utensil handle, substantially as shown.

FREDERICK K. STORM.
